(57) **CLAIM**

The ornamental design for a dispenser, as shown and described.

DESCRIPTION

FIG. 1 is a bottom-front perspective view of a dispenser showing our new design;

FIG. 2 is a top-front perspective view thereof;

FIG. 3 is a bottom-rear perspective view thereof;

FIG. 4 is a left side elevational view thereof;

FIG. 5 is a top plan view thereof;

FIG. 6 is a bottom plan view thereof;

FIG. 7 is a front elevational view thereof;

FIG. 8 is a right side elevational view thereof; and,

FIG. 9 is a rear elevational view thereof.

The portions of the dispenser shown in dashed lines form no part of the claimed design.
